UNITED STATES PATENT OFFICE.

PAUL STELLMACH, OF BROOKLYN, NEW YORK, ASSIGNOR TO SCOVILL MANUFACTURING COMPANY, OF WATERBURY, CONNECTICUT, A CORPORATION OF CONNECTICUT.

DISPLAY STAND.

Application filed January 13, 1925. Serial No. 2,058.

This invention relates to certain improvements in display stands or cases particularly adapted for displaying articles in shop windows, counters, or the like.

5 It is a special object of the invention to provide a display stand or case of attractive appearance which will permit a clear view of the articles and in which the articles may be readily positioned in the case and 10 removed therefrom.

A further object of the invention is to produce a display stand or case having pockets of different heights so as to accommodate articles of different heights as, for instance, 15 cards of safety pins, and which will be so shaped that the contents of the case may be visible from different angles as it stands on a counter or the like.

It is a further object of the invention to 20 produce a stand which can be cheaply made but which will be sufficiently strong to stand a certain amount of rough handling, so that it will not be easily damaged in use or in shipment.

25 With these and other objects not specifically referred to in view, the invention consists in certain novel parts, arrangements and combinations which will be fully described in connection with the accompanying 30 drawings and the novel features pointed out in the claims hereunto appended.

In these drawings—

Figure 1 is a perspective view of the improved case or stand;

35 Figure 2 is a plan view of Figure 1;

Figure 3 is a vertical sectional view taken on the line 3—3 of Figure 1;

Figure 4 is a sectional view taken on the line 4—4 of Figure 1;

40 Figure 5 is a partial sectional view taken on the line 5—5 of Figure 3, and

Figure 6 is a detail view showing one way of assembling the parts of the stand.

Referring now to these drawings, the 45 stand or case selected to illustrate the invention is one capacitated to hold a number of articles of different size and length as, for instance, cards of safety pins of different sizes. It will be understood, of course, that 50 the invention is not to be restricted to this use but that other articles than safety pin cards can be displayed and sold from the case.

The case or stand embodying the inven-

tion will include a back 1, ends 2, 3, a front 55 4 and a bottom 5. The stand is divided by partitions 6 into a number of article holders or pockets 7, 8, 9, 10 and 11. To give an attractive appearance and to permit articles of different lengths to be positioned in the 60 pockets so as to project above the tops thereof for ready grasping, the stand is, as shown in Figure 1, constructed so that the tops of the pockets are symmetrically stepped, the highest pocket 9 preferably being in the center of the stand with the lower pockets on each side thereof, this stepping being indicated generally by the numeral 12 in Figures 1 and 5.

To permit the articles to be readily viewed, 70 the front wall is panelled at each of the pockets, as indicated at 13, 14, 15, 16 and 17 in Figure 1, and if desired, the large central pocket 9 may have a cross-piece 18 having curved sides 19 to add to the attractiveness of the stand. 75

To enable articles in the stand to be seen through the paneling from various angles as the case stands on a counter or like place, the front of the stand, as shown in plan in Figures 2 and 3, is curved from end to end so that as a person approaches or views the stand from different angles, the articles in some of the pockets are in view, this adding to the saleability of the articles which are 85 held in the stand.

The stand may be made of any suitable material and the parts assembled in various ways. In the particular stand selected to illustrate the invention, the parts are made 90 of pasteboard which may be covered with a colored or designed paper of any suitable design or character, this producing an effective and, at the same time, a simple and cheap structure. In erecting the stand, there is provided a back piece 20 which, at its bottom, is outwardly bent to form the base piece 21 which forms the bottom of the pockets. The base piece is slotted, as indicated at 22, from the back toward the front, the slot, however, not extending entirely across the base. The partitions, likewise, are provided with a slot 23 toward their bottoms, which slot receives the unslotted portion 24 of the base so that the partitions are held 100 in the base. The partitions preferably extend below the base, as indicated in Figures 3 and 6, this extending portion 105 25

forming a leg or rest for supporting the stand. The front edge of the base is, furthermore, to strengthen the parts, turned up, as indicated at 26 in Figure 6, except at the 5 two end pockets.

The front of the case is made from a blank, cut or stamped, to form the panels, this blank, below the paneling, being formed with a foot piece 27 which is secured 10 by pasting against the flange 26 on the base, thus forming a rigid structure. The front blank is also formed with wings 28 and 29 which form the outer side walls of the 15 pockets 7 and 11, and these wings are bent around the back, as shown at 30 in Figure 4, and secured to the rear side of the back by pasting or otherwise. If desired, an additional back piece 34 may be provided for evening off the stand at the back so that it 20 presents a smooth surface and for further strengthening the stand.

The front is also stamped to form wings 31, 32, 33 and 34 which are bent around, as 25 shown in Figure 1, the upper edges of the partitions and secured thereto by pasting or otherwise, thus holding the partitions firmly in position.

With the construction shown, a display stand or case of very attractive appearance 30 has been produced, one which is simple and cheap to make but which, at the same time, is durable, and one in which a number of articles of different heights may be advantageously displayed and easily removed and 35 replaced.

While the stand has been shown and described in its preferred form, it will be understood that a stand embodying features of the invention may be produced in ways 40 other than that specifically shown and described, and the invention is not to be limited to such particular way of forming and assembling the parts of the stand.

What is claimed is:

45 1. A display case or stand comprising a back piece bent outwardly at its lower edge

to form a base or bottom, a front piece secured to the base and having wings bent around and secured to the back piece at the rear to form the ends of the stand, partition 50 pieces of different heights secured to the base dividing the stand into pockets open at the top, flaps on the front piece secured around the upper part of the partition pieces and to the back, and cutouts in the front piece 55 opening into the pockets.

2. A display case or stand comprising a back bent angularly to form a base, a front of convex shape having wings bent angularly thereto to form the ends of the stand 60 and secured to the back, said front and back being formed with symmetrical stepped portions, and partitions at the steps dividing the case into pockets of different height, said partitions extending below the base and 65 forming supports.

3. A display case or stand comprising a back piece bent outwardly at its lower edge to form a base or bottom, a front piece secured to the base and having wings bent 70 around and secured to the back at the rear to form the ends of the stand, slots in the base extending partially the width thereof, partition pieces having tongues engaging the slots and extending below the pieces 75 dividing the stand into pockets of different heights open at the top, and flaps on the front secured around the upper part of the partition pieces and to the back.

4. A display case or stand comprising a 80 base, a back, a front piece having wings bent angularly thereto to form the ends of the stand and secured to the back, a supplementary back piece secured between the ends of the wings, partition pieces seated on the 85 base, and flaps on the front pieces secured to the upper portion of the partition pieces and to the back.

In testimony whereof, I have hereunto set my hand.

PAUL STELLMACH.
